UNITED STATES PATENT OFFICE

97,076

DESIGN FOR AN ADVERTISING VEHICLE

Ernest J. B. La Lumiere, Cranston, R. I.

Application November 5, 1934, Serial No. 53,891

Term of patent 14 years

To all whom it may concern:

Be it known that I, Ernest J. B. La Lumiere, a citizen of the United States and residing at Cranston, county of Providence, Rhode Island, have invented a new, original, and ornamental Design for Advertising Vehicle, of which the following is a specification, reference being had to the accompanying drawing, forming a part thereof.

Fig. 1 is a side elevation of the novel design; and
Fig. 2 is a top plan view thereof.

I claim:

The ornamental design for an advertising vehicle substantially as shown.

ERNEST J. B. LA LUMIERE.
